UNITED STATES PATENT OFFICE.

JAMES EDWARD DOWD, OF HIAWATHA, UTAH.

REVERSIBLE GLOVE.

1,241,941:

Specification of Letters Patent. Patented Oct. 2, 1917.

Application filed September 8, 1916. Serial No. 118,992.

To all whom it may concern:

Be it known that I, JAMES E. Dowd, a citizen of the United States, and a resident of Hiawatha, in the county of Carbon and State of Utah, have invented certain new and useful Improvements in Reversible Gloves, of which the following is a specification.

One of the principal objects of my invention is to provide a glove, made preferably of rubber, or allied material, designed more particularly for the use of surgeons which may be used indiscriminately on either hand; such a glove that may when pulled off of a user's hand (which in a rubber glove necessitates turning it inside out by pulling down on the wrist portion) be replaced upon the same hand without turning again, or if desired, be placed upon the opposite hand.

Another object of the invention is to provide a one piece or molded glove in which the thumb is arranged in a neutral position, so that the glove may be used on either hand and may be reversed or turned inside out at will and in the new position be used indiscriminately on either hand.

With these and other objects in view which will become apparent as the description proceeds, the invention resides in the constructions, combinations and arrangements hereinafter described, and claimed, and illustrated in the accompanying drawing, in which like reference characters designate like or corresponding parts throughout the several views, and in which;

Figure 1 represents a plan view of a glove constructed in accordance with my invention;

Fig. 2 represents a view in section taken transversely on the plane indicated by the line 2—2 of Fig. 1.

Referring more particularly to the drawing, it will be seen that the glove constitutes the usual hand portion 5, wrist portion 6, fingers 7 and thumb 8. In forming the glove, I make the same preferably of one piece, by molding it from rubber or allied material.

The shape of the glove on opposite sides of a plane cutting centrally through the

fingers and thumb longitudinally thereof, is the same, that is, the glove is not made to fit the right hand or the left hand, specifically, but is made to fit either hand and the thumb 55 8 is arranged in a neutral position, that is, equally between the top and bottom faces of the glove, so that the glove may thus be slipped either upon the right hand or upon the left hand.

That portion of the glove indicated generally by the area A inclosed by the dotted lines B, at the base of the thumb, is made with an excess of material on both sides of the glove, so that the thumb 8 may without undue pulling or strain be swung to either side so as to readily fit either the right hand or the left hand. The glove may readily be turned inside out and replaced upon the same hand, so that it will thus be found to 60 be of use particularly as a surgeon's glove and of peculiar advantage, where only one hand of the surgeon is to be protected by a glove. The glove which I have provided fills the need in the practice of surgery of 65 a glove that after being taken off may be placed upon either hand without re-turning. A further advantage of the use of such a glove as I provide is the fact that it would 70 obviate the necessity of having right and left hand gloves sorted out in the operating room. It may here be noted that the surgeons' gloves are sterilized by boiling and that it is desirable to use gloves with as little handling as possible, and the glove which 75 I provide may be readily subjected to sterilization, and will always be ready to put on either hand without reversing, or the necessity of sorting out to perfect the pairs. Furthermore, the glove may, when desirable, be readily pulled off and put back on the same hand so as to give a fresh uncontaminated surface.

Although I have described the preferred embodiment of my invention, I may desire 80 to make such changes in the construction, combination and arrangements of parts thereof, as do not depart from the spirit of the invention or the scope of the appended claims.)

I claim:

1. A surgeon's glove made of seamless

material, and having its thumb arranged in a neutral position, and having an excess of material provided at the base of the thumb on both sides of the glove, whereby the glove 5 may be turned inside out and replaced upon the same hand without affecting the fit of the glove.

2. A seamless rubber glove so shaped as to be exactly alike on both sides of a plane cutting centrally through the fingers and 10 thumb of the glove longitudinally thereof, an excess of material being provided at the base of the thumb on both sides thereof.

JAMES EDWARD DOWN
